CHIMNEY VENTILATOR

Gottlieb F. Zucker, Chicago, Ill.

Application January 10, 1945, Serial No. 572,156

8 Claims. (Cl. 98—66)

1

The present invention relates to ventilators and more particularly to a chimney ventilator or similar structure.

It is an object of the present invention to provide an improved efficient relatively simple and inexpensive ventilator particularly adapted for chimneys having no moving parts or elements.

It is a further object of the present invention to provide a ventilator of improved construction for creating a vacuum on the side of the ventilator opposite to the side against which the wind may be blowing for drawing air or smoke out of the ventilator.

It is a still further object of the present invention to provide a ventilator which substantially prevents down-drafts and which is relatively simple to affix to a chimney.

Other and further objects of the present invention subsequently will become apparent by reference to the following description taken in connection with the accompanying drawing wherein

Figure 1 is a perspective view of a ventilator embodying the present invention;

Figure 2 is a side view of the ventilator shown in Figure 1;

Figure 3 is a cross sectional view as seen in the direction of the arrows along the line 3—3 of Figure 2;

Figure 4 is a perspective view of a mounting collar for the present invention;

Figure 5 is a perspective view of the removable door of the device shown in Figures 1 and 2; and

Figure 6 is an enlarged cross sectional view of one of the vertical V strips.

The draft efficiency of a chimney, particularly a rectangular or square chimney, varies in accordance with the direction of the wind. The wind in a certain direction may cause a back draft in the chimney thus reducing the efficiency thereof and causing incomplete combustion thereby producing smoke and unburned particles of fuel to accumulate in the chimney, in the furnace, and also to filter through cracks or seams in the chimney into the interior of the building.

To obviate the above mentioned disadvantage, it has heretofore been proposed to utilize ventilators of various types having movable elements such as dampers operated in response to the wind pressure. Such moving elements have a relatively short life due to the movement and to

2

the heat to which the elements are subjected, and furthermore are not efficient. Since such movable elements or devices require frequent repair and readjustment it is desired to obviate such elements.

In accordance with the present invention an efficient ventilator structure is provided having no moving parts and yet being capable of ready manufacture and assembly upon the building structure such as the chimney with which it is to be employed.

Figure 1 shows a chimney 10 having the usual cap 11 upon which is positioned a housing 12 usually secured to the headstone 11 in any suitable manner. The housing 12 over a substantial portion of its area is punched or pressed into a plurality of vertical elements 13 in the form of a plurality of parallel strips. The upper portion of the housing 12 is imperforate so as to form a substantially continuous band or border 14 above which is supported a cover plate 15 by suitable supporting straps or members 16. The cover plate 15 has an area substantially greater than the cross sectional area of the housing 12. Spaced 25 a short distance above the cover plate 15 is an auxiliary plate 17 secured by suitable means such as the bolts 18. The auxiliary plate 17 is spaced from the main cover plate 15 by a vertical wall structure 19 which is set inwardly from the outer edges of the plate 17 a short distance. The vertical wall structure 19 beneath the auxiliary plate 17 produces an effect of creating on the leeward side a vacuum or suction action to assist in drawing out the air and smoke from within the housing 12.

As may be seen from Figures 1, 2, and 3 the vertical strips 13 with the exception of the corner pieces are formed so as to have a generally V-shaped cross section. The bottom of the V, as 40 may be seen from Figure 6, is rounded so as to provide an improved action in the wind. This rounded bottom shape offers reduced resistance to the outward passage of the smoke and thus facilitates egress of smoke from the structure. 45 It also smoothly redirects outwardly, wind tending to enter the structure from the outside, thus increasing resistance to the entrance of approaching wind into the structure, and aiding in drawing the smoke therefrom. The width of the strips 50 13 is such that when they are formed into a V-

shaped cross section the relatively narrow openings 21 are provided between adjacent strips 13. In order to facilitate the manufacture of the present device three sides of the housing 12 are formed of a single piece of material so as to form all four corners of the housing 12. At each of the four corners of the housing 12, the corner vertical strip 22 is arranged at such an angle to the plane of the vertical strip so that the outer edges thereof substantially coincide with a plane passing through the outer edges of the V-shaped strips 13. Thus the openings adjacent the corner members 12 with respect to the adjacent vertical strips 13 are no greater than the openings between two V-shaped strips 13. If, therefore, the wind is from one side of the housing 12 or at an angle relative to two sides of the housing 12, the corner strip 22 prevents the wind from readily entering the openings between the vertical strips. Thus there is prevented the creation of even a partial down-draft action by the wind.

In order to facilitate the installation of the ventilator 12 on the cap 11 of the chimney 10 one side of the housing 12 is formed as a removable panel or door 23 having a lower portion 24 corresponding to the lower portion of the housing 12, and an upper portion 25 corresponding to the upper portion of the housing 12. Adjacent the upper edges of the lower and upper portions 24 and 25 respectively are a plurality of members 26 arranged to engage the interconnecting portion between two parallel side walls. After the hooks 26 have been placed in position a suitable screw member 27 is arranged to engage a threaded aperture to retain positively in position the removable door or side wall 23. The removable door or side wall 23 facilitates the installation of the housing 12 on the corner 11. The housing 12 adjacent its lower portion is provided with inwardly projecting portions such as the corrugation 20 as seen in Figure 1 or inwardly extending angle irons 28 as seen in Figures 2 and 3. These inwardly projecting members 27 or 28 are arranged to cooperate with an adjustable collar shown in perspective in Figure 1 and in cross section in Figures 2 and 3. The adjustable collar 4 is formed of four angle iron shaped members 29 each provided with a horizontal slot 31 for receiving a suitable bolt or fastening member 32. The collar formed of the members 29 therefore is arranged for adjustable positioning within the interior of the chimney cap 11 in the manner shown in Figure 2 from which it will be apparent that the fastening bolts 32 rest upon the top surface of the cap 11. After the rectangular collar shown in Figure 4 has been positioned as shown in Figures 2 and 3 concrete or cement is poured in between the collar 29 and the lower portions of the side walls of the housing 12 so as to engage either the inwardly projecting members 27 or 28. Thereafter the removable side wall 23 is placed in position and the ventilator 12 is in readiness for operation.

It has been found that a ventilator of the structure shown and described substantially prevents the creation of any back-draft within the ventilator or within the chimney as connected thereto regardless of the direction in which the wind may be blowing in any instance. While for the purpose of illustrating and describing the invention a rectangular ventilator has been shown, it of course will be appreciated that any other shaped ventilator may be employed while embodying the same principles of invention. For example the ventilator may be circular or of other

cross sectional shape, and the wind in passing about or away from the ventilator creates a vacuum which causes the air or smoke to be drawn out of the ventilator on the side at which the vacuum is created. This of course assists a steady flow of the smoke or heated gas out of the ventilator and chimney. It has been noted that the vertical walls 19 provided between the upper and lower plates 15 and 17 enhance or improve the chance of creating a partial vacuum to facilitate the ventilating action.

By providing a ventilator of the type shown having a substantial portion of the vertical wall area divided into vertical parallel strips, a larger portion of which are each formed into members having a substantially V-shaped cross section, the passage of the wind into the chimney opening is substantially prevented. The openings between adjacent strips preferably is but a fractional portion of the width of the strips. From the foregoing description it will be appreciated that there has been provided an efficient chimney ventilator which is relatively simple to manufacture and install and in which there are no moving parts or elements so that the useful life of the ventilator is limited only by the corrosive action of the smoke or heated gases flowing out of the chimney.

While for the purpose of illustrating and describing the present invention a preferred embodiment has been shown in the drawing, it is to be understood that the invention is not to be limited thereby since such modifications in the form, construction and the arrangement of the parts is contemplated as is apparent from the spirit and scope of the invention set forth in the accompanying claims.

This invention is hereby claimed as follows:

1. A generally rectangular chimney ventilator comprising a housing having vertical walls, the major portion of the area of each of said walls being punched into a plurality of parallel vertical strips, one strip at each corner being arranged at an angle of substantially forty-five degrees relative to the side walls, the remaining parallel vertical strips each being formed so as to have a substantially V-shaped cross section with the edges thereof directed outwardly from said housing to provide ventilating openings between adjacent strips, said openings being a fractional part of the width of said strips, the edges of said strips extending substantially to the planes interconnecting the corner strips, a cover plate for said housing mounted in spaced apart relation to the top thereof, said plate having an area greater than the horizontal cross section of said housing, an auxiliary plate of smaller size mounted above said first plate in spaced relation thereto, and vertical wall means interconnecting said upper and lower plates.

2. A chimney ventilator comprising a housing having vertical walls, the major portion of each of said side walls being punched into a plurality of parallel vertical strips each formed so as to have a substantially V-shaped cross section with the edges thereof directed outwardly from said housing to provide relatively narrow ventilating openings therebetween, an adjustable rectangular collar adapted to be mounted within and adjacent to the top surface of the chimney, means extending inwardly from the lower portion of the vertical side walls of the housing connected with said collar to anchor said housing to a chimney, a cover plate of substantially greater area than the horizontal area of said housing mounted in

5

spaced relation to the top thereof, an auxiliary plate of smaller size mounted above said first plate in spaced relation thereto, and vertical wall means interconnecting said upper and lower plates, said vertical wall means being positioned inwardly from the outer edges of said auxiliary plate.

3. A generally rectangular chimney ventilator comprising a housing having vertical walls, three of said walls being formed of an integral sheet of material so as to form the four corners of said side walls, the major portion of said sheet of material being punched into a plurality of parallel vertical strips, the vertical strip at each corner being arranged at equal angles to adjacent walls, the remaining parallel vertical strips each being formed so as to have substantially V-shaped cross sections with the edges thereof being directed outwardly from said housing substantially to a plane interconnecting the corner strips, said strips having relatively narrow ventilating openings therebetween of the order of a fractional part of the width of said strips, a removable wall member for the remaining wall of said housing, said removable member having a substantial portion of the area thereof punched into a plurality of similarly arranged and shaped parallel vertical strips, a cover plate for said housing mounted in spaced relation to the top thereof, said cover plate having an area substantially greater than the horizontal cross section of said housing, an auxiliary plate of smaller size mounted above said first plate in spaced relation thereto, vertical wall means interconnecting said upper and lower plates, said vertical wall means being positioned inwardly from the outer edge of said auxiliary plate, an adjustable rectangular collar adapted to be mounted within and adjacent to the surface of the chimney, and means extending inwardly from the lower portion of said housing for engagement by concrete to be placed between said collar and the inside of the lower portion of said housing thereby to anchor said housing to a chimney.

4. A generally rectangular ventilator for a chimney comprising a housing having vertical walls, the major portion of the area of each of said walls being punched into a plurality of parallel vertical strips, the corner strip at the junction of said walls being relatively flat and having its edges extending outwardly, the remaining vertical strips each being formed so as to have a substantially V-shaped cross section with the edges thereof directed outwardly from said housing and extending substantially to the plane interconnecting the edges of the corner strips, at least two of said vertical walls having adjacent the lower portion thereof inwardly extending members adapted to cooperate in securing the ventilator to a chimney, and an adjustable rectangular collar adapted to be mounted within and adjacent to the top surface of the chimney whereby said collar, said inwardly extending portions of said walls, and the top of said chimney may be held together by an interconnecting mass such as concrete.

5. A generally rectangular ventilator for a chimney comprising a housing having vertical walls, said walls having upper and lower margin portions, the portion intermediate said upper and lower margin portions being punched into a plurality of parallel vertical strips, the corner strip between adjacent walls being flat and arranged at an angle of substantially forty five degrees to the planes of the adjacent side walls, the remaining vertical strips each being formed so as

6

to have a substantially V-shaped cross section with the edges thereof directed outwardly from said housing to provide relatively narrow ventilating openings between adjacent strips, the edges of said sections extending substantially to planes interconnecting the outer edges of the corner strips.

10 6. A generally rectangular ventilator for a chimney comprising a housing having vertical walls, said walls having upper and lower margin portions, the portion intermediate said upper and lower margin portions being punched into a plurality of parallel vertical strips, the corner strip between adjacent walls being flat and arranged at an angle of substantially forty five degrees to the planes of the adjacent side walls, the remaining vertical strips each being formed so as to have a substantially V-shaped cross section with the edges thereof directed outwardly from said housing to provide relatively narrow ventilating openings between adjacent strips, the edges of said sections extending substantially to planes interconnecting the outer edges of the corner strips, an adjustable rectangular collar adapted to be mounted within and adjacent to the top surface of a chimney, and means extending inwardly from the lower portion of said housing for engagement by concrete to be placed between said collar and the inside of the lower portion of said housing thereby to anchor said housing to a chimney.

15 7. A generally rectangular chimney ventilator comprising a housing having vertical walls, three of said walls being formed of an integral sheet of material, the major portion of said sheet of material between upper and lower border portions being punched into a plurality of parallel vertical strips, the vertical strip at each of the four corners of said housing being arranged at an angle of substantially forty five degrees to adjacent walls, the remaining parallel vertical strips each being formed so as to have substantially V-shaped cross sections with the edges thereof directed outwardly from said housing to provide relatively narrow ventilating openings therebetween of the order of a fractional part of the width of said strips, the edges of said V-shaped cross section formed strips in each wall being substantially in the plane interconnecting the edges of the corner strips, a removable wall member for the remaining wall of said housing, said removable member between the border portions thereof being punched into a plurality of parallel vertical strips each shaped so as to have a substantially V-shaped cross section, an adjustable rectangular collar adapted to be mounted within and adjacent to the top of the chimney, and means extending inwardly from the lower portions of said housing for engagement by concrete to be placed between said collar and the inside of the lower portion of said housing thereby to anchor said housing to a chimney.

20 8. A generally rectangular ventilator for a chimney comprising a housing having vertical walls each having upper and lower margin portions, the portion intermediate said upper and lower margin portions being punched into a plurality of parallel vertical strips, the corner strip between adjacent walls being flat and arranged at an angle of substantially forty-five degrees to the planes of the adjacent side wall, the remaining strips each being formed so as to have a generally V-shaped cross section with a rounded bottom and straight sides, the edges of said sides being directed outwardly from said housing to pro-

vide relatively narrow ventilating openings between adjacent strips, said edges extending substantially to planes interconnecting the outer edges of the corner strips.
